[57] CLAIM

The ornamental design for a food mold, as shown and described.

DESCRIPTION

FIG. 1 is a top plan view of a food mold showing my new design;

FIG. 2 is an end view of FIG. 1 as seen from the top thereof;

FIG. 3 is an end view of FIG. 1 as seen from the bottom thereof;

FIG. 4 is a plan view showing the reverse side of FIG. 1; and

FIG. 5 is a side view of FIG. 1 looking from the right side thereof.

The left side of FIG. 1 is a mirror image of FIG. 5.

FIG. 5
